United States Patent Office

Des. 202,450
Patented Sept. 28, 1965

202,450

DISPLAY BOX

Samuel Braun, Rye, N.Y., assignor to B.C.N. Design
Products, Inc., Amityville, N.Y., a corporation of New York

Filed Apr. 7, 1965, Ser. No. 84,658

Term of patent 14 years

(Cl. D58—12.7)

FIG. 1

FIG. 2

Des. 202,450

PAGE 2

FIG.3

FIG.4.

FIG. 5.

FIG. 6.

FIG. 1 is a front elevational view of a display box embodying my design;

FIG. 2 is a top plan view thereof;

FIG. 3 is a rear elevational view thereof;

FIG. 4 is a bottom plan view thereof;

FIG. 5 is a side elevational view thereof; and

FIG. 6 is a perspective view thereof with the lid in open position.

The broken lines in FIG. 6 are for illustrative purpose only.

I claim:

The ornamental design for a display box, as shown and described.
